UNITED STATES PATENT OFFICE.

WILLIAM L. JONES, OF GALLIPOLIS, OHIO.

CAN-FILLING APPARATUS.

1,423,944.

Specification of Letters Patent.

Patented July 25, 1922.

Application filed January 23, 1918. Serial No. 213,302.

To all whom it may concern:

Be it known that WILLIAM L. JONES, a citizen of the United States of America, residing at Gallipolis, in the county of Gallia and State of Ohio, has invented certain new and useful Improvements in Can-Filling Apparatus, of which the following is a specification.

My invention relates to apparatus for filling cans of varying capacity with tomato pulp although it will be obvious that my improvement is capable of use in filling cans with practically any other liquid. It is especially advantageous in the filling of five 15 gallon cans, though one of the noteworthy characteristics of my invention resides in its adaptability for supplying cans of all sizes with the proper amount of liquid by extremely simple regulation.

20 The invention finds embodiment in a main reservoir above one or more intermediate feed tanks. These intermediate feed tanks are designed to approximate the capacity of the cans to be filled and are provided with 25 valve structure designed to cut off the supply to the intermediate tank when such intermediate tank is discharging and to admit the supply when the intermediate tank is not discharging.

30 The control of the discharge from the intermediate tank is particularly novel. It is applied in consecutive steps by the rising level of liquid in the cans being filled, as follows: First, the supply of air to the intermediate tank above the liquid therein is cut off by the rising liquid in the can being filled, which slackens the discharge. Then, the discharge part of this intermediate tank is covered by the rising liquid and 40 the discharge is stopped. At any time after this, the discharge valve may be closed.

The intermediate tank may be provided with discharging nipples of any desired size. And the cans to be filled are mounted 45 upon a platform which is vertically movable into and out of position for filling. The extent of this vertical movement and the length of these nipples may be varied to regulate the quantity fed.

50 The preferred embodiment of my invention is shown in the accompanying drawings wherein similar characters of reference designate corresponding parts and wherein—

55 Figure 1 is a front elevation of a struc-

ture that may be utilized by me in carrying my invention into effect.

Figure 2 is a side elevation of the structure shown in Figure 1.

Figure 3 is a detail in section showing 60 one of my intermediate tanks cut off from the main supply tank and feeding a full stream to a can.

Figure 4 is a similar detail in section showing the air pipe cut off by the rising 65 liquid in the can and showing a consequent reduction of feed to the can.

Figure 5 is a similar detail showing the liquid in the can risen over the mouth of the feed nipple with a complete cessation 70 of feed as a consequence.

Figure 6 is a similar detail showing intermediate tank cut off by its valve from supplying the can and with its inlet valve open to receive liquid from the supply tank. 75

Figure 7 is a front elevation of the can supporting platform.

Figure 8 is a side elevation of the structure shown in Figure 7.

Figure 9 is a side elevation of this plat- 80 form raised.

Figure 10 is a section on line 10—10 of Figure 7.

In the drawings, my improvement is shown as comprising a main tank 1 beneath 85 which is located a series of intermediate tanks 2 and a platform. The operation of this platform will be described later and it will suffice to say that it is designed to support a tray for the reception of a plurality of cans which may be raised into receptive position by such platform.

The tank 1 is of considerable size and the intermediate tanks 2 are each of slightly greater capacity than the largest cans that 95 are to be filled. The tank 1 is connected to each of the intermediate tanks 2 by a short pipe 3 having a rotatable valve 4 therein. The base of this tank 2 is provided with a similar pipe 5 having a rotatable 100 valve 6 therein and a discharge delivery nipple 7 which may be replaced by nipples of varying sizes.

The valves 4 and 6 carry crank arms 8 and 9 to which are connected adjustably extensible links 10 and 11 which are in turn connected to a cross-piece 12 upon a controlling 105 slide shaft 13. The position of the valves 4 and 6 and their connection to this controlling shaft 13 is such that move- 110

ment of the shaft to either of its positions, indicated by full and dotted lines, will open one valve when the other is closed and vice versa.

5 Extending out of the upper end of each intermediate tank 2 is an air pipe 14 which passes upwardly to a point above the highest liquid level in the main tank 1 and then returns downwardly to a point adjacent the 10 delivery nipple 7 terminating preferably about a half inch below the terminus of the delivery nipple 7.

The supporting platform for the cans generally designated carries a vertically 15 movable platform 15 having rollers 16 disposed thereon for the reception of a tray 17. The vertically movable platform 15 is designed to receive the cans upon a tray when in lower position and to be elevated 20 so as to bring such cans into receptive position with the discharge nipples of the intermediate tanks and the lower ends of the air pipes extending thereinto.

The movement into and out of receptive 25 position may be effected by means of links 18 connected to wrist pins 19 adjustably clamped in guideways 20 of discs 21 by nuts 22. These discs 21 are mounted upon a shaft 23 which is oscillated for raising or lowering the platform 15 by means of a lever 24. On the shaft 23 is a counter-weight 25 which extends laterally from the shaft 23 when the platform is lowered but which moves downwardly into vertically pendant relation 35 to the shaft during the raising of such platform, adding its weight to the force applied in raising the platform 15 and the lever 24 from the position shown in Figure 8 to the position shown in Figure 7.

40 The lever 24 is provided with a trigger mechanism comprising a main link 26 slidably mounted upon such lever 24 and having an offset end 27 which is adapted to fit alternately in the socket 28 or the socket 45 29 for locking the platform and lever in either raised or lowered position. This trigger mechanism further comprises a bell crank 30 connected by a link 31 to a lateral finger hold 32. It also has an extension 33 which serves as a supplemental handle for operating the trigger mechanism.

The slidable member 26 of the trigger mechanism is normally pressed longitudinally by a spring and its offset or tongue 55 end rides upon an acute surface in between the slots 28 and 29, automatically dropping into either slot when it reaches proper position.

In the operation of my apparatus, the 60 cans upon a tray are placed upon lowered platform 15. The trigger of the lever is operated to raise the tongue 27 from its socket and the lever is lifted, with the assistance of the counter-weight to move the 65 platform upwardly and bring the cans into

receptive position. When the upper position of the platform is reached, the trigger mechanism is released, the tongue 27 automatically springs into the socket 28 and the platform is thus locked in raised position. 70

When in this position, the nipple 7 and the lower end of the air pipe extend into each can a distance which has been predetermined. Then the controlling slidable 75 shaft 13 is moved to close the valve 4 and open the valve 6. Liquid starts to pass through the valve 6 into the can in a full stream, air being expelled around the nipple and also passing upwardly through the air 80 pipe 14 into the intermediate tank. This operation is shown in Figure 3. A full stream is delivered until the liquid in the can reaches and closes the lower end of the pipe 14, as shown in Figure 4. When this 85 happens, the air supply is cut off from the upper end of the intermediate tank, whereupon the delivery of liquid to the can materially diminishes, developing in fact into a gurgling delivery. Shortly after this, the 90 rising liquid in the can reaches and covers the delivery end of the nipple 7. Whereupon further supply of liquid to the can automatically ceases, as indicated in Figure 5. At any time after this, the controlling shaft 13 95 may be moved to close the valve 6 and open the valve 4 bringing about a condition such as is shown in Figure 6. After this, the trigger mechanism upon the lever may be released to permit lowering of the can supporting platform, which is effected by the weight of the filled cans overbalancing the counter-weight 25. 100

It will be obvious that I have provided a can filling mechanism which measures 105 practically without gauges or triggers set in advance. The supply of liquid is first diminished and then shut off completely, the whole measuring and computing operation being effected by the natural operation 110 of filling the can. There is practically no waste and obviously the mechanism is extremely simple. No close fit between the nipple and can mouth is necessary. My device will operate as well on an open mouth 115 can as on any other kind.

Having thus described my invention what I claim is:

1. Apparatus for filling cans comprising a main reservoir, a plurality of intermediate 120 feed tanks positioned directly below said reservoir, a delivery nozzle for each feed tank, a separate inlet nozzle connecting each intermediate tank with said reservoir, valves controlling the said nozzles whereby when 125 one set of nozzles is closed the other set is open, and a vent pipe extending from each intermediate tank to a point above the highest liquid level in said main reservoir and having its inlet end terminating immedi- 130

ately below the delivery nozzle of each intermediate tank and of such construction in relation to said delivery nozzle that it will enter the receptacle to be filled, where-
5 by the filling of said receptacle will finally bring about cutting off of the intermediate tank from the atmosphere which will be immediately followed by a complete cessation of flow to the said receptacle by the 10 covering of the end of the said delivery nozzle.

2. Apparatus for filling cans comprising a main reservoir, an intermediate feed tank positioned directly below said reservoir, an 15 inlet nozzle connecting said reservoir and said tank, a separate nozzle for discharging the liquid from said tank, valves controlling said nozzles and means connecting the valves whereby the opening of one will close 20 the other, and a vent pipe for controlling the flow of liquid in the intermediate tank, one end of said pipe being connected to the top of the tank and extending from said tank to a point above the main reservoir

and the other end terminating below the dis- 25 charge nozzle of the tank.

3. Apparatus for filling cans comprising a main reservoir, a plurality of intermediate feed tanks, inlet nozzles connecting said reservoir and said tank, separate nozzles for 30 discharging the liquid from said tanks, vent pipes for controlling the flow of liquid from each intermediate tank, one end of each of said pipes being connected to the top of each tank and extending from the tank to a point 35 above the main reservoir and the other end terminating below the discharge nozzle of each tank, and a vertically movable and adjustable platform for moving the cans into filling position relative to said discharge 40 nozzles and vent pipes.

In testimony whereof I hereby affix my signature in the presence of two witnesses.

WILLIAM L. JONES.
